TIE WIRE CLAMP

Patrick Joseph Corcoran, Memphis, Tenn.

Application April 5, 1950, Serial No. 154,078

4 Claims. (Cl. 254—29)

1

This invention relates to certain new and useful improvements in clamping means for concrete forms, and particularly relates to new and useful improvements in clamping means for tie wires used in conjunction with such forms.

In concrete work it is customary to employ molds or forms for retaining the concrete as it is poured in order that it may set properly, and tie wires, extending through the form and the concrete contained therein, have been employed to retain the walls of the forms, particularly where footings of substantial depth are to be formed.

Much difficulty has heretofore been encountered in securely and properly anchoring the tie wires and in retaining them with proper tension so as to prevent bulging or sagging of the forms and effect retention in desired position.

The principal object of this invention is to provide a simple, efficient and economical device for accurately and positively clamping form tie wires and for adjusting and maintaining tension on such wires.

A further object of the invention is to provide a tie wire clamp which may be removably mounted exterior the concrete form and may be employed in one location and when the concrete at such location has set up may be removed and applied to a different or new location.

A further object of the invention is to provide an adjustable tie wire clamp which is adaptable for use with wires of varying diameters.

A further object of the invention is to provide a new and novel arrangement for positively engaging concrete form tie wires and for readily disengaging the clamp from such wires when it is desired to remove the clamping device.

A further object of the invention is to provide a tie wire clamp which includes a casing having a roller journaled therein, a traction member journaled and interposed over the roller, a clamping follower engaging the traction member outwardly from its traction surfaces and means for clamping the traction member against the roller member.

And a further object of the invention is to generally improve the design, construction and utility of tie wire clamp means.

The means by which the foregoing and other objects of the present invention are accomplished and the manner of their accomplishment will readily be understood from the following specification upon reference to the accompanying drawings, in which:

Fig. 1 is a sectional elevational view taken

2

on the line I—I of Fig. 3 showing the tie wire clamp of the present invention mounted upon a form and engaging a form tie wire.

Fig. 2 is a side elevational view of the tie wire clamp of this invention; and

Fig. 3 is a sectional view taken as on the line III—III of Fig. 2.

Referring now to the drawings in which the various parts are indicated by numerals, the tie wire clamping means of the present invention are adapted for use in connection with a mold or form 11 of the type generally employed in concrete work for retaining the wet concrete for setting, which form 11, as is well known, includes side walls made up in conventional manner from a plurality of boards.

The form 11 is provided with a plurality of tie wires 13, one of which is shown in the drawings, the tie wires being spaced at intervals throughout the form. It also is customary to provide spacers 15 to limit movement of the form walls toward each other. Preferably tie wires 13 are anchored to the outer side of one of the form walls, as at 17, and project inwardly through the wall and across the space between the walls, thence through the opposite wall and project outwardly therebeyond.

The clamping device of this invention is adapted to be mounted on the form adjacent the free end of the tie wire 13, and the clamping means consist of a casing or housing 19 of generally rectangular cross section, the front and rear walls of the housing being apertured as at 21 to receive the free end of the tie wire 13.

The side walls of housing 19 are provided with elongated slots 23, 24, in the lower ends of which slots opposite reduced end portions of a roller member 25 are rotatably and slidably mounted. Superposed over roller member 25, and also rotatable and slideable in slots 23, 24, is a traction member 27 having a central corrugated zone or band 29, the width of the corrugated band being preferably slightly in excess of the diameter of apertures 21. Traction member 27 adjacent the opposite ends of corrugated band 29 is provided with roller sections 31 which are free of corrugations for the purposes hereinafter mentioned. The roller sections 31 lie adjacent the side walls of housing 19.

Traction member 27 outwardly of housing 19 is provided with an angularly formed head 33, preferably of hexagonal shape as illustrated and adapted to be engaged by a conventional wrench or other tool for the purpose of rotating the traction member.

Resting upon the roller sections 31 are the depending legs 35 of a preferably channel shaped follower 37. The follower 37 is freely movable within housing 19 and the web of the follower provides a seat against which the lower end of an adjustable thrust member, illustrated as a screw 39, bears, the screw 39 being threadedly engaged with a suitable aperture formed through the top of housing 19 for adjustment and extension into housing 19. Preferably the housing 19 is provided with an aperture diagonally crossing an upper corner adapted to receive a suitable removable hanging means, such as nail 41, by which the housing may be removably suspended from the side of form 11.

In the use of the device the free end of tie wire 13 is inserted through one of the housing apertures 21 and projected between the corrugated band 29 of traction member 27 and lower roller 25. The housing and enclosed instrumentalities are moved closely adjacent to form 11 and the housing is removably suspended from the side of the form through the use as of hanging nail 41. With the device thus positioned screw 39 is tightened upon follower 37 bringing the legs 35 into close engagement with roller sections 31 and clamping wire 13 between corrugated band 29 and roller 25. Tension may then be applied to wire 13 by rotation of traction member 27 through the application of a wrench or other suitable tool to traction member head 33 and through the use of such tool effecting rotation of the traction member.

As the smooth roller sections 31 underlie the legs 35 of follower 37 rotation of the traction member is not prevented, the corrugated band 29 being segregated from engagement with the leg ends. As traction member 27 is rotated the corrugated band, which is clamped against wire 13 by the action of screw 39 and follower 37, frictionally engages the wire and draws it between the corrugated band and roller 25, satisfactorily applying tension to the wire. When the desired tension has been applied the tool employed may be removed from the traction member head 33 and the engagement of follower legs 35 with the traction member in many instances will be adequate to prevent reverse rotation of the traction member and roller member and will retain the wire in tensed condition.

If desired, as in cases of extra tension, additional tightening of screw 39 may be accomplished effecting a tighter engagement of follower 37 with the traction member and braking return or reverse rotation of the traction member.

Preferably the device is provided on the side face adjacent the traction member head 33 with an abutment member 43 spaced from the head 33 so as to not impede the desired rotation of the head, but adapted to receive a supplemental removable abutment member, such as nail 45, which will fit within the space between the head 33 and abutment 43 and by engaging the head 33 prevents undesired rotation. When the concrete in the form has satisfactorily set up screw 39 may be loosened, unclamping the wire 13, hanging nail 40 may be withdrawn and the entire device removed from the free end of the tie wire.

I claim:

1. Clamping means adapted for use with a form tie wire comprising a hollow housing, a roller member, a traction member, said members being positioned within said housing in superposed parallel relation with said traction member overlying said roller member, and being vertically

slidable and rotatably supported by the sides of said housing, said traction member being provided with a central corrugated traction zone and opposite uncorrugated end portions adjacent said sides, a follower within said housing overlying said traction member and slidably in said housing, said follower having an upper seat and a pair of spaced depending legs, said legs being respectively seated on said traction member end portions outwardly from said central zone, screw means threadedly engaging the top of said housing and extending through said top for abutment with said follower seat to force said follower into engagement with said traction member, said traction member having a head extending beyond said housing, means removably mounted exterior said housing engaging said head to limit rotation of said traction member, and access apertures formed in the front and rear of said housing, the diameter of said apertures being less than the width of said traction zone, said apertures being aligned with the lower portion of said zone and the upper portion of said roller member for guiding a tie wire into said housing between said zone and said roller member.

2. Clamping means adapted for use with a form tie wire comprising a hollow housing, a roller member, a traction member, said members being positioned within said housing in superposed parallel relation with said traction member overlying said roller member and being vertically slidably and rotatably supported by the sides of said housing, said traction member being provided with a central corrugated traction zone and opposite uncorrugated end portions adjacent said sides, a follower within said housing overlying said traction member and slidably in said housing, said follower having an upper horizontal seat and a pair of spaced depending legs, said legs being respectively seated on said traction member end portions outwardly from said central zone, thrust means adjustably engaging the top of said housing and extending through said top for abutment with said follower seat to force said follower into engagement with said traction member, said traction member having a head extending beyond said housing, and access apertures formed in the front and rear of said housing, the diameter of said apertures being less than the width of said traction zone and aligned with the lower portion of said zone and the upper portion of said roller member for guiding a tie wire into said housing between said zone and said roller member.

3. Clamping means adapted for use with a form tie wire comprising a hollow housing, a roller member, a traction member, said members being positioned within said housing in superposed parallel relation with said traction member overlying said roller member and being vertically slidably and rotatably supported by the sides of said housing, said traction member being provided with a central corrugated traction zone and opposite uncorrugated end portions adjacent said sides, a follower within said housing overlying said traction member and slidably in said housing, said follower having an upper horizontal seat and a pair of spaced depending legs, said legs being respectively seated on said traction member end portions outwardly from said central zone, thrust means adjustably engaging the top of said housing and extending through said top for abutment with said follower seat to force said follower into engagement with said traction member.

tion member, said traction member having a head extending beyond said housing.

4. Clamping means adapted for use with a form tie wire comprising a hollow housing having opposite slots in its sides, a cylindrical roller member, a cylindrical traction member, said members being positioned within said housing and having end portions of reduced size slidably and rotatably supported by the slots in the sides of said housing, said traction member being provided with a corrugated traction zone, a follower within said housing perpendicular to one of said rotatable members and slideable in said housing, said follower having a seat and spaced legs extending from said seat, said legs being respectively seated on said one rotatable member, thrust means adjustably engaging said housing

and extending into abutment with said follower seat to force said follower into engagement with said one rotatable member.
